PERFORATING MACHINE

Joseph Fossa, Lynn, Mass., assignor to United
Shoe Machinery Corporation, Paterson, N. J., a
corporation of New Jersey

Application February 13, 1937, Serial No. 125,594

22 Claims. (Cl. 164—88)

This invention relates to perforating machines and is herein illustrated as embodied in a machine for producing ornamental perforations in shoe part blanks such as vamps or tips.

5 Perforating machines of the type referred to as heretofore constructed commonly comprise a punch which is movable heightwise of a work support to perforate a blank positioned thereon and movable transversely of the support subsequent 10 to each punching operation to advance the work along the support thus to form a row of perforations in the blank, usually along edge portions thereof. These machines are usually operated at speeds to produce from 400 to 500 reciprocations 15 of the punch per minute. In constructions heretofore in use the parts are subjected to considerable wear partly because of their inertia at the speeds mentioned and partly because of the play between the various parts which further results 20 in noisy operation.

In view of the foregoing, it is an object of the present invention to provide a perforating machine of improved construction which can be satisfactorily operated quietly at comparatively 25 high speeds without excessive wear of the parts.

To this end, and as illustrated, the invention consists in the provision of a perforating machine in which there is a work support, a punch mounted for movement heightwise of the support, and a continuously rotating cam spaced 30 from the punch, together with a manually-controlled member between the cam and the punch and movable heightwise thereof for causing the cam to force the punch toward the work support 35 to produce perforations in work positioned upon the support.

Preferably, and as shown, the punch is mounted at the free end of a lever pivotally connected to the frame of the machine and is resiliently 40 forced toward the cam, the member for causing operation of the punch being in the form of a wedge having faces for engaging corresponding faces of the lever so that the wedge can be moved to take up the space between the cam and punch 45 thereby to initiate one or more punching operations. As illustrated, the punch lever is oscillated to cause the punch to advance the work along the support by means of a continuously oscillating drive shaft connected to the lever by a link the 50 effective length of which can be varied to vary the length of feed movements of the punch.

The construction above set forth eliminates play between the punch and its operating mechanism thereby reducing wear and noise in operation with 55 the result that the machine can be satisfactorily

operated at speeds of 1500 cycles or more, per minute, but at the same time the punch can be quickly rendered inoperative to perforate the work without placing excessive strain upon the operating parts.

5 The invention further provides novel mechanism including means for ensuring a single operation of the punch, a presser foot for holding down the work during portions of the cycle of operations and at such times as the cam is ineffective to cause operation of the punch, and an adjustable gage for guiding edge portions of the work as it is advanced over the support.

10 These and other features of the invention are disclosed in the accompanying drawings and in 15 the following detailed specification and are set forth in the claims.

In the drawings,

Fig. 1 is a front elevation of a perforating machine illustrating one embodiment of my invention;

Fig. 2 is a plan view of the machine;

Fig. 3 is a side elevation partly in section of the machine;

Fig. 4 is a front elevation of a portion of the 25 punch operating mechanism, parts of the machine being shown in section;

Fig. 5 is a side elevation partly in section of the punch operating mechanism;

Fig. 6 is a plan view partly in section of portions 30 of the punch operating mechanism;

Fig. 7 is a detailed view partially in section of the punch lever and the punch operating lever;

Fig. 8 is a vertical cross section taken along the line VIII—VIII of Fig. 7;

Fig. 9 is a detail of the members shown in Fig. 7 with the punch operating lever in inoperative 35 position;

Fig. 10 is a side view partly in section of the punch reciprocating and feeding mechanism;

Fig. 11 is a rear view of the mechanism shown 40 in Fig. 10;

Fig. 12 is a plan view of the mechanism shown in Fig. 10; and

Fig. 13 is a detail view partly in section showing the mechanism for centering the punch.

45 As illustrated in Figs. 1 and 3 the machine comprises a frame 10 carrying a work table 12 adapted to support work to be operated upon, such as a quarter or other shoe part, which can 50 be advanced across the table into operative position relatively to a punch 14 which is arranged to be depressed by a cam 16 which causes the punch to penetrate the work, the punch 14 being mounted in a punch carrier and feed lever 18 which is 55

oscillated to cause the punch to feed the work across the table between successive punching operations there being a presser foot 20 to hold the work down upon the table during the punching operation, and an edge gage 22 to guide the work during feeding operations.

The punch 14 (Figs. 4, 5 and 10) comprises punch tubes 24 which are carried by a punch plate 26 mounted in a dovetailed groove 28 at the lower 10 end of a shank 30 and held in a position in the groove by a retaining plate 32 and sets crew 34. The shank 30 has a cavity 36 through which the waste material formed in the punching operations may pass. The shank 30 is slidably mounted 15 in an opening 37 in a boss 38 at the forward end of the lever 18, heightwise movement of the shank relatively to the boss being prevented by a collar 40 at the upper end of the shank. The lever 18 is mounted upon a horizontal pivot 42 which is 20 carried at the lower end of an oscillating forked link 44 mounted upon a pin 46 on the frame 10. The forward end of the feed lever 18 which carries the boss 38 extends between upright portions 48 (Fig. 13) of an extension 50 of the frame, 25 these upright portions being effective to guide the boss in its oscillating movements. The forward end of the lever 18 and the plunger are normally held in raised position by a spring 52 (Figs. 1, 5 and 10) carried by a curved rod 54, the upper 30 end of the spring being secured to the frame and the lower end of the spring being connected to a pin 56 mounted in the lever 18 and having a flattened portion 58 which is adapted to engage the lower end of the rod 52 to limit upward 35 movement of the punch.

For causing reciprocations of the punch at the will of the operator there is provided a wedge member 60 adapted to form an operative connection between the cam 16 and the lever 18. 40 This wedge member 60 is carried by a link 62 which is arranged to be reciprocated under manual control by mechanism hereinafter described. The member 60 carries a hardened steel wear plate 64 secured thereto by screws 66 and by 45 dowels 67. The underside of the member 60 is provided with cam teeth 68 (Figs. 7, 8 and 9) engageable by similar teeth 70 mounted upon opposite sides of the boss 38. As best shown in Fig. 9, the teeth 68 have beveled faces 72 terminating in flat portions 73 and the teeth 70 have corresponding beveled faces 74 and flat faces 75, the construction being such that when the link 62 is in one position the member 60 rests upon the faces 75 but when the link is moved to the left, 50 in Fig. 10, the teeth 68 ride up on the teeth 70 to raise the member 60 which is held in raised position when the teeth 68 rest upon the flat faces 75. The lever is shown in its raised position in Figs. 5, 7 and 8 and in its lower position 55 in Figs. 9 and 10. In the lower position the wear plate 64 is clear of the high part of the cam by about one-thirty-seconds of an inch with the result that as the cam is rotated this motion is not transmitted to the lever 18. However, when 60 the link 62 is moved to the left and assumes its upper position the wear plate 64 is operated upon by the cam to cause a depression of the forward end of the lever 18 and consequently of the plunger to produce a punching operation. The cam shaft 76 mounted in the frame and rotated by means of a pulley 78. The cam is lubricated by oil felt 80 carried by a bracket 82 on the frame.

The mechanism for oscillating the lever 18 in 75 producing work feeding movements of the punch

comprises a shaft 84 (Figs. 3, 5, 6 and 10), which is driven by an eccentric 86 on the drive shaft 76 and through an arm 88. Upon the end of the shaft 84 is an enlarged portion 90 which is connected to the lever 18 by means of a link 5 92 mounted upon the pivot 42 and carrying a pin 94 through which is connected an adjustable link 96 which extends through a slot 98 in a sleeve 100 secured to the portion 90. The link 96 has a cylindrical portion 102 slidably mounted in 10 the sleeve and located between nuts 104 which are arranged to be moved axially of the sleeve by a screw bolt 106 which extends through a screw plug 108 in the upper end of the sleeve, the adjustment being made by means of a nut 110. 15 A spring 112 (Fig. 10) extending between the upper end of the sleeve and the link 96 tends to force the link upwardly along a line between the center of the pin 94 and the center of the shaft 84. Variation in the position of the link 94 thus 20 will result in a variation of the throw of the lever 18 in such manner as to vary the length of feed of the punch. When the center of the pin 94 is positioned to coincide with the axis of the shaft 84 the link 92 will oscillate about the axis 25 of the shaft without imparting any movement to the link 18 with the result that there is no feed movement of the punch. The link 96 is provided with a pointer 114 arranged to move along a scale 116 on the sleeve 100 during the adjustment of the link for the purpose of indicating the length of the feed. It is to be noted that when the pin 94 is brought into alignment with the axis of the shaft 84 the latter does not transmit motion to the link 92 with the result that 30 there are no work feeding movements of the punch. This adjustment is usually made when it is desired to produce perforations at widely 35 spaced points in the work.

Mechanism is provided for oscillating the link 40 62 under manual control to render the cam effective in causing perforating operations of the punch. This mechanism comprises a pin 118 (Figs. 5 and 10) connecting the link 62 to an arm 120 of a lever 122 mounted upon the pivot 42 and 45 having a second arm 124 carrying a pivot 126 upon which is mounted one end of a link 128 the other end of which is connected at 130 to a plate 132 mounted upon the stud 46. The plate is adapted to be rotated by a forked lever 134 50 mounted upon a pin 136 carried by the enlarged portion 90 on the end of the shaft 84. The lever 134 has two arms 138 having at their ends hooks 140 and 142 adapted to engage, respectively, studs 144 and 146 secured to the plate 132. The lever 55 134 is continuously oscillated up and down by the shaft 84 and when the lever is rotated in either direction one of the hooks will, during the next oscillation of the lever, be brought into engagement with one of the studs and upon downward 60 movement of the lever the plate 132 will be rotated to effect movement of the link 62 in a lateral direction. As shown in Fig. 5, the hook 140 has just engaged the stud 144 and has rotated the plate 132 in a counterclockwise direction with 65 the result that the link 62 has moved to the left to raise the wedge member 60 so that the cam 16 will be operative during its next rotation to force the punch toward the anvil. In Fig. 10 the hook 142 has just engaged the stud 146 and rotated the plate 132 in a clockwise direction with 70 the result that the link 62 has been moved to the right and the wedge member 60 has been lowered so that the cam will not engage the striking plate 64 with the result that the punch 75

will not be reciprocated, in a heightwise direction, but will merely oscillate back and forth with the lever 18.

The lever 134 is operated by springs 148 and 150 mounted upon a rod 152 one end of which is pivotally secured at 154 to the lever 134. The springs engage a block 156 carried by an arm 158 on a shaft 160 which extends toward the rear of the machine (Figs. 2 and 3) and carries at its rear end an arm 162 connected to a treadle rod 164. The arm 158 is normally forced in a counterclockwise direction in Fig. 1 by a spring 166 (Fig. 3) which presses upon the under side of the arm 162. The springs 148 and 150 upon rotation of the arm 158 resiliently force the lever 134 to one of its two extreme positions in which one or another of the hooks will be thrown into position to engage one of the studs upon the plate 132.

It is to be noted that the various oscillating parts, particularly the lever 18, the link 52, and the lever 134 are made light in construction to reduce as far as possible the inertia of the parts.

In order to reduce the play between parts thereby to reduce noise and the likelihood of breaking or producing excessive wear of the various operating parts means is provided for preventing rapid rotation of the plate 132. To this end, there is provided a stop plate 168 (Figs. 10 and 12) pivoted at 170 upon the frame and arranged to engage either of two ears 172 formed upon the plate 132. The movement of the stop plate about its pivot is frictionally retarded by means of a spring 174 mounted upon a stud 176 extending through slot 178 in the stop plate, the spring operating to press the plate tightly against the surface of the frame with the result that when the plate 132 is moved angularly in either direction one of the ears will engage the stop plate 168 and its movement retarded to the extent that it is brought gradually into one of its extreme positions.

The plate 132 is held in each of its extreme positions by means of a spring 180 (Fig. 1) surrounding a rod 182 one end of which is pivoted to the plate at 184 and the other end of which is carried by a stud 186 on the frame. It is to be noted that after the plate 132 has been swung through an angle of about 10° in either direction from the line between pivots 46 and 186 the spring 180 will serve resiliently to hold it in its extreme position.

Mechanism is provided for holding the plate 132 substantially in the position shown in Fig. 5 in which the wedge member is in operative position for a sufficient time for a single punching operation to take place. This mechanism comprises a lever 188 (Figs. 1 and 10), mounted upon the stud 186 and having a hook 190 adapted to engage a stud 192 upon the arm 158 when the latter has been rotated in a clockwise direction by momentary actuation of the treadle rod 164, the hook and the stud being held in engaging position by a spring 194. When in this position the lever 188 will hold the arm down with the result that the spring 148 will rotate the lever 134 in a counterclockwise direction and hold it in that position while it is oscillated up and down to engage the stud 164, thus initiating a punching operation. As the plate 132 is rotated, however, a tail portion 195 thereof engages an end 196 of the lever 188 rotating it in a direction to release the hook 190 from the stud so that upon the next oscillation of the lever 134 the hook 192 can engage the stud

146 to rotate the plate 132 in a direction to render the wedge member 60 inoperative.

I have provided a presser foot 20 adapted to hold the work down upon the anvil during the time the punch is penetrating the work and mechanism for intermittently raising the presser foot at such times as the punch feeds the work, this mechanism being such that the presser foot is held in its downward position when the cam is held in its downward position when the cam is ineffective to operate the punch. As shown in Figs. 1, 4, 6 and 13 the presser foot 20 is carried by a frame bracket 50, the presser foot being mounted upon a vertical slide 198 held in position on the bracket by a guideway 200 secured to the bracket by screws 202. The presser foot is normally forced in a downward direction toward the work support by a spring 203 extending between a perch 204 on the top of the slide and a perch 206 on the bracket. The slide has a laterally extending projection 208 from which extends upwardly and laterally a hook 210 adapted to engage a second hook 212 carried by a link 214 secured to a pivot 216 mounted eccentrically of the axis of the cam 16. This arrangement is such that as the cam rotates the link 214 will raise the presser foot against the tension of the spring 203 during that part of the rotation of the cam when the high part thereof is out of engagement with the wear plate 64, or in other words, at such a time as the lever 134 is being moved rearwardly to cause feed movements of the punch.

Mechanism is provided to insure that the presser foot 20 is down to hold the work against the anvil when the wedge 60 is inoperative to cause reciprocations of the punch heightwise of the anvil. To this end, there is provided means for disconnecting the hook 212 from the hook 210 when the wedge member is in its inoperative position. This mechanism comprises an arm 218 secured to the plate 132 having pivotally connected thereto at 220 a rod 222 which extends downwardly and through a spring perch 224 fastened to the link 214. Surrounding the rod is a spring 226 which extends between a collar 228 and the spring perch 224, the end of the rod being provided with nuts 229 adapted to engage the spring perch 224 when the rod moves to the left in Fig. 1 which occurs when the plate 132 is moved in a clockwise direction, resulting in swinging the link 214 about its pivot 216 so that the hook 212 is disconnected from the hook 210 at such time as the wedge member 60 is inoperative. This results in the spring 203 forcing the presser foot 20 toward the work support. When the plate 132 is moved in the opposite direction the collar 228 forces the spring 226 yielding against the spring perch 224 to force the hook 212 into position to engage the hook 210.

In order to raise the presser foot 20 when, for example, it is desired to present the work into operative position beneath the punch or to remove the work from the machine, I have provided a manually-controlled device comprising a lever 230 (Fig. 1), pivoted upon one of the frame portions 48 at 232, the upper portion of the lever being adapted to engage the under side of the projection 208 to raise the presser foot 20. The lever 230 is operated by means of a rod 234 an end of which is secured to a lever 236 pivotally mounted at 238 (Figs. 2 and 3) upon the upper portion of the machine frame and operated by a treadle rod 240.

When perforations are to be formed along a curved edge portion of the work the work must be shifted angularly with the result that the punch

is turned in its mounting during feed movements of the punch carrier. In order to return the punch to its normal position after such feed movement I have provided a punch centering device. This device comprises a plate 242 (Figs. 10 and 13) secured to the frame portions 48 by screws 244. The plate carries a plunger 246 positioned in an opening 248 and forced by a spring 250 into engagement with the shank 30 of the punch. The plunger is pointed and adapted to enter a V-shaped groove 252 in the punch. When the punch is turned angularly relatively to the bracket which occurs when operating upon curved edge portions of the work when the lever 18 is moved forwardly the plunger, acting in the groove, tends to cause the punch to return to its original position. It is to be noted that angular movement of the punch is limited by pins 254 (Fig. 3) secured to the lever 18 upon opposite sides of the punch receiving opening and adapted to engage beveled surfaces 256 upon the lower portion of the shank 30.

The gage 22 is adapted to contact with edge portions of the work in order to guide the latter as it is fed past the face of the anvil in such manner that the perforations produced by the punch will be equally spaced from the edge of the work. The marginal portions of the work are held down adjacent to the edge gage by a holdown member 257 (Fig. 4) secured to the shank portion of the gage by a screw 259. The holdown member is in the form of a leaf spring adapted to press upon the upper surface of the work, the amount of pressure exerted thereby being adjustable by means of a set screw 259.

The gage 22 is secured in position relatively to the punch in the following manner. As shown in Figs. 4 and 6, the plate 242 has an extension 250 which has therein a vertical slot 261 in which is positioned a projection 262 extending from the shank of the gage, said projection having a head 264 for retaining the shank in position in a lateral direction. The gage is normally forced downwardly and inwardly toward the direction of punch feeding movement by means of a spring 266 extending from a pin 268 carried by the shank of the gage to a pin 270 secured to the bracket. The work engaging portion of the gage can be adjusted inwardly or outwardly of the line of punch feeding movement by means of a screw 272, the end of which is adapted to engage the wall of one of the upright frame portions 48 thereby to limit inward movement of the gage.

In order to provide for movement of the gage into inoperative position when it is desired to operate upon central portions of the work there is provided a cam plate 274 pivoted at 275 in the plate 242 and having notches 276 and 278 adapted selectively to engage the projection 262 of the gage. As shown in Fig. 4, the projection is positioned in notch 276 of the cam in which position the gage is operatively located relatively to the punch. Upon rotation of the cam by a handle 280 the gage is raised upwardly and outwardly out of its operative position. During this movement the gage is moved outwardly by means of a guide member 282 which engages an edge portion 284 of the plate 242 which acts as a cam to force the gage outwardly.

I have provided an anvil to serve as a backing member to receive the blow of the punch after it has penetrated the work. This member preferably comprises a brass plate 292 (Fig. 4) which is supported at the upper end of a post 294 and clamped in position thereon by clamping mem-

bers 296 and 298, the clamping member 298 being secured to the post by a screw 300. The clamping member 296 is arranged to be tightened against the plate to lock it in position in engagement with the member 298 by means of an adjusting screw 302 (Figs. 1 and 3), there being a spring 304 positioned between the post 294 in the clamping member 296 to force the latter outwardly when the screw is loosened.

The table 12 is divided into two sections 306 and 308 which surround the anvil 292 and are clamped together along a line 310 to form a smooth work supporting surface. The rear section 308 is provided with depending ears 311 which are secured to the post 294 by screws 312. The forward section 306 of the table is provided with ears 314 which are pivotally mounted upon screw bolts 316 so that the section can be rotated forwardly about the axis of the bolts when it becomes necessary to replace or adjust the anvil 292. The forward section 306 is secured in position in contact with the rear section 308 by means of a leaf spring 318 adapted to engage a pin 320 carried by the rear section 308.

Vertical adjustment of the anvil relatively to the punch is obtainable by means of a wedge 322 adapted to engage a beveled face 324 at the lower end of the post 294. The heightwise position of the post is adjusted by a screw 326 engaging a portion 328 of the frame and having a collar 330 which enters a slot 332 in the wedge by which the latter can be moved in or out in order to accomplish adjustment of the post.

In the operation of the machine the treadle rod 240 is depressed to raise the presser foot 20 so that a blank can be located in operative position relatively to the punch 14 upon the table 12 after which the treadle rod is released to permit the presser foot to hold the blank upon the table. The treadle rod 164 is then depressed with the result that the arm 158 is moved in a clockwise direction (Fig. 1) to force the lever 134 in a counterclockwise direction. Upon oscillation of the lever heightwise by the oscillation of the shaft 84, the hook 140 (Fig. 5) of the lever will engage the stud 144 of the plate 132 and effect counterclockwise rotation of the same causing link 128 to rotate the lever 122 in a direction to move the link 62 to the left which effects movement of the teeth 68 upon the teeth 70 until the wedge member 60 occupies its upper position (Fig. 7) with the wear plate 64 in engagement with the continuously rotating cam 16 which causes depression of the punch 14 to perforate the work. The lever 44 is then oscillated to move the punch lever 18 in a direction to cause the punch to advance the work along the table and then to return it to its original position. During this time the cam 16 through the link 214 raises the presser foot 20 clear of the work but permits its return at the end of the return movement of the punch. This cycle of operations continues as long as the treadle is depressed but when it is released the hook 142 is pulled to the right and engages the stud 146 to move the plate 132 in a clockwise direction which causes the link 62 to move to the right with the result that the wedge is moved out of contact with the cam and the latter no longer causes operations of the punch which continues to oscillate back and forth with the lever 18 but is held spaced from the cam by the rod 54 which engages the pin 56. As the plate 132 rotates the lever 218 (Fig. 1) rotates with it causing the rod 222 to release the hook 212 from the hook 210, thus

permitting the presser foot to be depressed by the spring 203.

When a single perforation is to be produced a quick depression and release of the treadle rod 5 moves the arm 158 in a clockwise direction (Fig. 1), until the hook 190 engages the stud 192 which retains the arms when the rod is released in position to force the lever 192 into position in which the hook 140 will engage the stud 144 causing 10 movement of the wedge to depress the punch. During rotation of the plate 132 the tail portion 195 thereof rotates the lever 188 to release the arm 158 so that upon subsequent oscillation of the lever 134 the latter will operate to depress the 15 wedge rendering the cam inoperative to move the punch.

Having described my invention, what I claim as new and desire to secure by Letters Patent of the United States is:

20 1. A perforating machine comprising a work support, a punch mounted for movement heightwise of the support, a rotary cam, manually controlled means normally forming an operative connection between the punch and cam for causing the punch to penetrate work positioned upon the support and operable selectively to disconnect the punch from the cam, and means for oscillating the punch transversely of the support to advance the work along the support.

30 2. A perforating machine comprising a work support, a punch mounted for movement heightwise of the support, a rotary cam spaced from the punch, and a wedge positioned between the cam and the punch and movable in a heightwise direction to cause the punch to penetrate work positioned upon the support.

35 3. A perforating machine comprising a frame, a work support carried by the frame, a punch pivotally mounted upon the frame for oscillation relatively to the support, a rotary cam, means normally operative to force the punch toward the cam, and a manually controlled member normally forming an operative connection between the punch and cam for causing movement of the 40 punch toward the support and operable selectively to render the punch inoperative.

40 4. A perforating machine comprising a frame, a work support carried by the frame, a punch pivotally mounted upon the frame for oscillations heightwise and transversely of the support, a rotary cam, means normally operative to force the punch toward the cam, a stop for limiting movement of the punch toward the cam, and a wedge insertable between the punch and cam for forcing 45 the punch toward the support to penetrate work positioned thereon.

50 5. A perforating machine comprising a frame, a work support carried by the frame, a punch carrier pivotally mounted upon the frame for movement transversely of the support, a punch mounted in the carrier, a rotary cam spaced from the punch carrier, and a wedge pivotally mounted upon the frame between the cam and punch carrier and movable to close the space between the 55 cam and the punch for causing movement of the punch toward work positioned upon the work support.

55 6. A perforating machine comprising a frame, a work support carried by the frame, a punch carrier pivotally mounted upon the frame and having a free end portion extending over the support, a rotary cam spaced from the free end of the punch carrier, a punch mounted in the carrier, a wedge member mounted upon the punch carrier, and 70 manually controlled means for moving the wedge

into position in engagement with the cam for causing downward movement of the punch toward the support.

7. A perforating machine comprising a frame, a support carried by the frame, a punch carrier 5 pivotally mounted upon the frame and having a free end portion which extends in a transverse direction over the support, a punch mounted in said free end portion, a rotary cam for causing movement of the punch toward the support, and 10 means for oscillating the punch carrier transversely of the support to feed work positioned thereon.

8. A perforating machine comprising a frame, a work support carried by the frame, a punch 15 carrier pivotally mounted upon the frame, a punch positioned in the carrier, a rotary cam located adjacent to the punch carrier, a member between the punch carrier and the cam causing movements of the punch toward the support, 20 means for controlling the operation of the member comprising a link pivotally mounted upon the frame, and manually controlled means for moving the link into either of its positions, thereby to move the member respectively into operative or 25 inoperative relation to the cam.

9. A perforating machine comprising a frame, a work support carried by the frame, a punch lever pivotally mounted upon the frame, a punch carried at an end of the lever, a rotary cam, a wedge 30 member movable into position between the cam and the lever for causing movement of the punch toward the support, means for oscillating the lever to cause the punch to advance work across the face of the support, means for moving the wedge 35 into or out of operative position relatively to the cam comprising a lever pivotally mounted upon the frame and operatively connected to the wedge, a plate pivotally mounted upon the frame, a link connecting the plate and the lever, and a latch 40 carried by the punch lever and oscillating therewith adapted to engage either of two projections carried by the plate and operable selectively to rotate the plate in either direction thereby to cause movement of the wedge.

45 10. A perforating machine comprising a frame, a work support carried by the frame, a lever pivotally mounted upon the frame, a punch carried by the lever, a rotary cam, means normally operative to force the punch toward the cam, means on the 50 frame normally operable to space the punch from the cam, and means positioned between the punch and cam and selectively operable to take up the space between the punch and cam to cause movement of the punch toward the support.

55 11. A perforating machine comprising a frame, a work support carried by the frame, a lever pivotally mounted upon the frame and having a free end portion extending adjacent to the support, a punch mounted in the free end portion, a continuously rotating cam for causing movement of the punch toward the support, manually operable means for selectively rendering the cam either operative or inoperative to move the punch, a presser foot slidably mounted upon the lever adjacent to the punch, means normally operative to force the presser foot toward the support, means operable intermittently to raise the presser foot, and means for rendering the last-mentioned means inoperative when the cam is rendered inoperative to move the punch.

60 12. A perforating machine comprising a frame, a work support carried by the frame, a punch carrier pivotally mounted upon the frame, a punch mounted upon a carrier, a rotary cam spaced from 70 75

the punch carrier, a wedge movable into position between the punch carrier and cam for causing the cam to move the punch toward the support, a presser foot slidably mounted upon the punch carrier, means normally operative to force the presser foot toward the support, a member operatively connected to the cam for intermittently raising the presser foot, and means operable when the wedge is inoperative to cause movement of the punch for rendering the cam inoperative to raise the presser foot.

13. A perforating machine comprising a frame, a post carried by the frame, a table associated with the post and comprising two sections, one of which is fixedly secured to the post and the other of which is pivotally mounted thereon, and means for locking the movable section in fixed position.

14. A perforating machine comprising a frame, an anvil carried by the frame, a punch carrier pivotally mounted upon the frame, a punch mounted upon the carrier, a plate carried by the punch carrier and having a slot therein, a gage member having a portion which normally extends into position adjacent to the punch and having a shank portion positioned in the slot, and a cam pivotally mounted upon the plate for moving the shank portion along the slot to locate the gage in inoperative position relatively to the anvil and punch.

15. A perforating machine comprising a frame, a lever pivotally mounted upon the frame and having a free end, a punch mounted in the free end of the lever, an oscillating shaft, a link connected to the lever and to the shaft for reciprocating the lever, and an adjustable connection between an end of the link and the shaft for varying the position of the end of the link relatively to the axis of the shaft thereby to vary the length of the stroke of the lever.

16. A perforating machine comprising a frame, a link pivoted upon the frame, a pin carried by the link, a punch lever one end of which is connected to the pin, a punch carried by the other end of the lever, an oscillating shaft, a movable pivot carried by the shaft, and a link connecting the pin and movable pivot for oscillating the punch lever.

17. A perforating machine comprising a frame, a link pivoted upon the frame, a pin carried by the link, a punch lever one end of which is connected to the pin, a punch carried by the other end of the lever, an oscillating shaft, a pivot carried by the shaft, a link connecting the pin and pivot for causing reciprocation of the lever to effect feed of work by the punch, and means varying the position of the pivot relatively to the axis of the shaft to vary the length of the work feed movements of the punch.

18. A perforating machine comprising a frame, a work support, a punch mounted upon the frame for movement heightwise of the support, a rotary cam for causing movement of the punch toward

the support, a spring normally operative to force the punch toward the cam, means for spacing the punch from the cam, and manually controlled means between the cam and punch for causing one or more operations of the punch 5 upon work positioned upon the support.

19. A perforating machine comprising a work support, a punch mounted for reciprocation toward and from the support, a continuously rotating cam, means normally operative to force the 10 punch toward the cam, a stop operative to limit movement of the punch toward the cam to insure clearance between the cam and punch, a wedge located between the cam and punch, and manually controlled means for rendering the 15 wedge operable to cause the cam to depress the punch thereby to perforate work positioned upon the support.

20. A perforating machine comprising a work support, a punch carrier mounted for movement 20 heightwise of the support, a punch mounted in the carrier, a continuously rotating cam, projections upon the carrier having an inclined face, and means for operatively connecting the cam to the punch comprising a member located between 25 the cam and punch having an inclined face for engaging the corresponding face upon the carrier and a flat face for engaging the cam.

21. A perforating machine comprising a work support, a punch carrier mounted for movement 30 heightwise of the support, a punch mounted in the carrier, a continuously rotating cam, projections upon the carrier having inclined faces, and means for operatively connecting the cam to the punch comprising a member located between 35 the cam and punch having inclined faces for engaging the corresponding faces upon the carrier and a flat face for engaging the cam, and manually controlled means for varying the position of the member in a heightwise direction to move 40 the flat face from inoperative position to a position in which it engages the cam.

22. A perforating machine comprising a work support, a rotary cam spaced from the support, a punch positioned between the support and the 45 cam mounted for movement heightwise thereof, a member between the punch and cam for causing the punch to penetrate work positioned upon the support, means for initiating a punching operation comprising a link connected to said 50 member, a rotatable plate for actuating the link, a continuously oscillating lever selectively movable into engagement with the plate for moving the plate in a direction to render the member inoperative or in a direction to render the member 55 operable to cause a punching operation, a manually operable member for moving the lever into engagement with the plate, and means for forcing the lever angularly in a direction to engage the plate during a portion of its oscillation.
